His Attorney.

UNITED STATES PATENT OFFICE

2,235,656

BASE FOR ELECTRICAL DEVICES

Georg Thal, Berlin, Germany, assignor to General Electric Company, a corporation of New York

Application July 12, 1940, Serial No. 345,245
In Germany July 7, 1939

2 Claims. (Cl. 176—32)

My invention relates to electric lamps in general and more particularly to lamps which are adapted to project only a narrow beam of light substantially in one direction. Still more particularly, my invention relates to a rotating base construction for such lamps whereby the lamp can be rotated in its socket after having been inserted therein.

In the case of electric lamps which are adapted to radiate light mainly in one direction, such as those used particularly for signaling purposes, headlight purposes and air-raid protection, it is frequently desirable to change the direction of light radiation by rotating the lamp in its socket. For this purpose, the lamp may be provided with a rotating base construction such as that described and claimed in Patent No. 2,165,987, Sobczak et al., issued July 11, 1939 and comprising an inner threadless sleeve cemented to the bulb neck, and an outer threaded or bayonet-type base shell rotatably mounted on said inner sleeve by means of an inwardly-extending annular rib spun into a corresponding annular groove in the inner sleeve. Such a construction does not provide of itself a very reliable electrical connection between the outer base shell and the inner sleeve, so that the continuity of lamp operation is not assured at all times. In addition, such a construction does not provide of itself a very firm mounting for the outer base shell, so that the latter is apt to wobble on the inner sleeve. As a result, the lamp itself is not supported very firmly in the lamp socket.

One object of my invention is to provide an electric lamp with a rotating base simple in construction and effective in operation which will insure, even during the rotational adjustment, a reliable electrical contact between the various parts of the base and between the base and the socket so as to maintain the flow of current to the lamp filament at all times.

Another object of my invention is to provide an electric lamp with a rotating base structure the rotating member of which is firmly mounted on the lamp so as to provide a firm support for the lamp in its socket.

The improved rotating base according to the invention comprises an inner sleeve cemented to the lamp bulb neck and enclosed by an outer contact sleeve or shell which is locked with respect to said inner sleeve against axial displacement relative thereto and which is limited in its rotation by suitable stop means. According to my invention, the inner sleeve is provided with outwardly projecting spring elements which en-

gage the surrounding outer sleeve and provide a reliable electrical contact between the inner and outer sleeves at all times as well as a firm mounting for the outer sleeve.

The rotating base makes it possible to rotate the lamp at will to the left or to the right by approximately 360° after the lamp has been screwed into a socket. The production and use of the base are simple because it is only necessary to slide the outer base shell over the end of the inner sleeve either before or after the latter is cemented to the lamp bulb, and to roll the edge of the outer base shell into an annular groove in the inner sleeve so that the interengaging annular rib and groove will permit rotation of the base but not an axial displacement or removal of the same.

Further objects and advantages of my invention will appear from the following description of a species thereof and from the accompanying drawing in which:

Fig. 1 is a longitudinal sectional view, partly in elevation, of an electric incandescent lamp for air-raid protection purposes provided with a base comprising my invention; and Fig. 2 is a cross-section on the line 2—2 of Fig. 1.

Referring to the drawing, the lamp there shown comprises a pear-shaped glass bulb 1 containing a stem tube 2, a supporting rod or arbor 3, and a filament 7, preferably a coiled tungsten wire, supported by a plurality of support wires 4 extending from said arbor and arranged in the form of a star. The opposite ends of the filament 7 are connected to a pair of leading-in or current-supply wires 5, 6. The bulb 1 is evacuated through an exhaust tube 8 which, after evacuation of the bulb, is tipped or closed off as shown in the drawing. The lamp bulb 1 is provided with an opaque light-absorbing coating 10 over its entire outer surface with the exception of a small laterally arranged light outlet window 9 which may be circular or of any other desired shape. If desired, the opaque coating 10 may be placed on the inner surface of the lamp bulb instead of on the outer surface. The portion of the lamp bulb in which the window 9 is located is made substantially flat, and the window 9 is made somewhat smaller than the flattened bulb portion, as shown, so that the opaque coating 10 also covers the edge 11 of the said flattened portion of the bulb wall. Because of the opaque bulb coating 10 formed with the small window 9 therein, the light of the lamp can be emitted only over a very narrowly limited space angle.

Attached to the neck 12 of the bulb is a rotat-

5 10 15 20 25 30 35 40 45 50 55

able base according to the invention comprising an inner threadless metal sleeve 13 cemented or otherwise secured to the bulb neck, and a conventional screw-threaded lamp base proper rotatably mounted on the inner sleeve 13 and comprising a threaded shell 14, an insulating body 15, and a bottom contact eyelet 16. The rim or edge of the shell 14 is formed with an annular rib 17 which fits into a corresponding annular groove 18 in the inner sleeve 13 to thereby provide the rotatable mounting of the base on the inner sleeve. The said annular rib 17 may be conveniently produced by spinning or rolling the metal of the threaded shell 14 into the annular groove 18 in the inner sleeve. By reason of the interfitting annular rib 17 and groove 18, the base proper can be rotated about the longitudinal axis of the inner sleeve 13 but is locked against axial displacement relative thereto.

20 To limit the rotational movement between the base proper and the inner sleeve 13, suitable stop means are provided comprising a lug 20 extending longitudinally from the edge 19 of the base shell 14 and a co-operating stop pin or projection 21 formed on the free or uncovered edge portion of the inner sleeve 13 and extending radially outward therefrom. Thus, after a certain amount of rotation of the base proper relative to the inner sleeve 13, the stop lug 20 will strike against 30 the pin 21 to thereby prevent further rotation. The arcuate extent or width of the lug 20 and of the stop pin 21 is preferably made relatively small so as to permit relative rotation between the base proper and the inner sleeve 13 approximating 360°. The stop pin 21 conveniently serves as the soldering point for one of the leading-in wires 5, the other leading-in wire 6 being soldered to the bottom contact eyelet 16 of the base proper.

In order to obtain, in each rotative position of 40 the base proper with respect to the inner sleeve 13 and during actual rotation therebetween, a reliable electrical connection between the base shell 14 and the inner sleeve 13, as well as a support which is secured against mechanical vibration, 45 the inner sleeve 13, at a point longitudinally spaced an appreciable distance from the interfitting annular rib 17 and groove 18, is provided

with a plurality of elastic or spring elements 22 preferably punched out of the sleeve at equally spaced points around the circumference thereof. The said spring elements 22 are bent slightly outward so as to press against the threads on the 5 threaded base shell 14. The outward pressure of the spring elements 22 against the inner side of the base shell thus insures the maintenance of an electrical contact between the base shell 14 and the inner sleeve 13 at all times, as well as 10 providing a firm support for the base proper on the inner sleeve 13 and consequently a firm support for the lamp in its socket.

While I have shown and described the invention as applied to electric incandescent lamps, it 15 is obvious that it may be applied equally well to electric discharge lamps and discharge tubes.

What I claim as new and desire to secure by Letters Patent of the United States is:

1. A base for electric lamps or similar devices 20 comprising an inner metal sleeve for attachment to the neck of the lamp bulb, and an outer shell shaped to engage a socket, said shell being rotatably mounted on and surrounding said inner sleeve and being locked against axial displacement 25 relative thereto, said inner sleeve being provided with a plurality of outwardly projecting spring elements punched out of the metal of said inner sleeve and engaging the inner side of said shell.

2. A base for electric lamps or similar devices comprising an inner sleeve for attachment to the neck of the lamp bulb and having an annular groove, and an outer shell surrounding said inner sleeve and formed with an annular rib extending 30 into said annular groove to thereby permit relative rotation between said shell and said inner sleeve while preventing axial displacement therebetween, said inner sleeve being provided with at least three outwardly projecting spring elements 40 located at a point longitudinally spaced an appreciable distance from said interfitting annular rib and groove, said spring elements being arranged at approximately equally spaced points around the circumference of said inner sleeve and 45 resiliently engaging the inner side of said shell.

GEORG THAL.
